Application October 4, 1948, Serial No. 52,764

43 Claims. (Cl. 66—48)

1

This invention relates to circular multi-feed hosiery knitting machines and methods of operating same, and more particularly to mechanism for fashioning multi-feed fabric in reciprocatory knitting to make heel and toe pockets in hosiery.

To produce narrowing and widening during the making of heel and toe pockets in the usual single-feed independent needle circular hosiery knitting machines, the needles are raised progressively out of action by two lifter picks, one operable on each direction of movement. However, a single dropper pick adapted to operate on both directions of movement is generally used to lower needles into action. With this arrangement it is conventional to knit the narrowed segment of a heel or toe pocket by raising one needle out of action at the beginning of each course. When it comes time to knit the widened segment, this action is continued and in addition the dropper pick lowers two needles into action at the end of each course. In this way the fabric is first narrowed one needle per course and then widened a net amount of one needle per course. This gives a closely-knit suture between the two gussets or segments of the ordinary heel.

Each lifter pick heretofore used in narrowing has usually been located on top of the cam over which the needles are cleared preparatory to entering the knitting wave. Because a lower face of that same cam is used to knit on a return stroke of the machine, it will be observed that the lifter picks are never in the path of the needles in a knitting wave approaching from the opposite direction.

To carry this general arrangement of picking in narrowing and widening over into the making of heel and toe pockets by multi-feed knitting has several difficulties. Using the conventional two lifter picks and one dropper pick for each oscillation in multi-feed machines, it is necessary to narrow for more than one course at the same time. This means that two needles have to be raised out of action together. An objectionable float or "tie-across" stitch is produced by this operation. Furthermore, the raising of two needles together produces eyelets at the suture. This is due to the fact that only one course of the group retains its stitches till widening. I have discovered how to construct a circular multi-feed hosiery knitting machine so as to knit a replica of the narrowed side of the suture of a conventional heel or toe pocket made on a single-feed machine. In my multi-feed machine I narrow by elevating the leading needle to in-

2

active level at the start of each course. In this way a series of successive courses of fabric are each individually narrowed in a single oscillation of the machine. I mount and manipulate the picks of my machine in such a way that a greater variety of constructions is possible on the narrowed and widened sides of the suture than has heretofore been obtainable in either single or multi-feed machines. The variety of sequences in picking which I can obtain gives sutures and gussets adapted to my need. My novel machine has a series of yarn feed points adapted to knit in a reciprocatory manner. It is characterized by the presence of one dropper pick operating in both directions and two lifter picks at each feed point. The two picks at any one feed point are adapted to act on movements in different directions. At least one of each pair of these lifter picks is located between each two stitch cams in the group of knitting cams in the path of ascending needle butts, i. e., in the knitting wave. I provide clearing cams under several stitch-drawing surfaces, each such clearing cam and the stitch-drawing surface under which it is located being sloped so that they are effective on needle movements in opposite directions. I locate clearing cams to operate under the stitch-drawing surfaces except the end ones of the entire group. I so locate these picks and shape the cams that in any one direction of movement of the needles they contact a given lifter pick and in the other direction they pass above or below that pick. In addition, the lifter picks can be made inoperative selectively without interfering with the remaining picks.

My invention will be shown and described embodied in the well-known Scott & Williams type of revolving needle cylinder independent needle circular hosiery knitting machine in which I have put two feeds, but it should be understood that it is equally applicable to such machines having three or more feeds. A two-feed machine of this general type is shown in the Lawson Patent No. 2,440,280, dated April 27, 1948.

45 In the drawings:

Figure 1 is a plan view of one-half of the cam ring and lifter picks of a two-feed Scott & Williams hosiery knitting machine made in accordance with one embodiment of my invention, showing the needles moving counterclockwise, one needle butt being shown raised out of action by the outer lifter pick of the pair at the right-hand feed. Another needle is shown about 50 to contact the inner lifter pick of the pair at 55

the left-hand feed. The top of the center stitch cam is shown broken away;

Figure 2 is a perspective view of the construction of Fig. 1, taken from the center of the machine with the needle butts omitted.

Figure 3 is a development of the knitting cams of Figs. 1 and 2 as seen from the center of the machine with needle butts moving from right to left, i. e., counterclockwise. The solid line showings of all the lifter picks illustrate their positions as the first needle butt of the active segment of needles contacts the outer lifter pick at the right-hand feed, while the dotted arrows and showings of the picks indicate their paths of travel as the leading active needle is lifted out of action at that feed, and their positions at the end of that lift. The number of needles and their spacing is only diagrammatic.

Figure 4 is a development similar to Fig. 3, showing in solid lines the positions of the parts as the leading active needle at the left-hand feed contacts the inner lifter pick. The dotted arrow and showing of the picks at that feed illustrate the movements of those picks while that needle is being lifted, and their position at the completion of that lift.

Figure 5 is a detail view on an enlarged scale of the outer lifter pick at the right-hand feed, showing the adjustment of the parts so that this pick will pick up two needles.

Figure 6 is a plan view of the cam ring and lifter picks and their controls in a modified embodiment in which there is mechanism to change the number of needles lifted by the inner lifter picks in addition to the outer lifter picks, as in Figs. 1 to 5.

Figure 7 is a perspective view of the construction of the right-hand feed of Fig. 6, seen from the outside of the machine, the inner lifter pick being ready to raise a single needle butt.

Figure 8 is a perspective view of the outer lifter pick of the left-hand feed of the embodiment of Figs. 1 and 2, showing the parts in solid lines when the pick is positioned to engage only a single needle at a time, and showing in dotted lines the position of the swivel cam when the pick is 45 to raise two needles at a time.

Figure 9 is a plan view of part of the cam ring and lifter picks of a two-feed embodiment of my invention using a modified form of inner lifter picks, the parts being shown with the inner picks in position to be engaged by needle butts. The top of the center stitch cam is shown broken away.

Figure 10 is a developed view similar to Fig. 4 but showing the modified inner lifter picks of Fig. 9.

Figure 11 is a perspective view from the center of the machine, of the left-hand feed of the embodiment of Figs. 9 and 10, showing the inner lifter pick in position to be engaged by a needle butt.

Figure 12 is a view in vertical section through the cam ring of Fig. 1 at the inner lifter pick of the left-hand feed, taken on the line 12-12 of that figure.

Figure 13 is a development of part of the needle circle of the modification of Figs. 6 and 7, showing in solid lines the leading active needle engaging the inner lifter pick at the left-hand feed after passing under the double center stitch cam. The pick is adjusted for a single needle lift. The figure also shows a sinker and part of its path in the usual sinker cap and indicates by a line 69 the approximate end of the robbing area under the center stitch cam.

Fig. 13A shows on a smaller scale than Fig. 13 the sinker wave S10 developed by the sinker and cams of Fig. 13 at both feeds.

Figure 14 is a perspective view of part of the bedplate, lifter picks and associated cams and controls of a modified form of my invention adapted to make the inner lifter picks ineffective to raise needles out of action during the widening operation.

Figure 15 is a development of the knitting cams and lifter and dropper picks of the modification of Fig. 14, some of the dotted line showings of the inner lifter picks illustrating the positions of those picks when they have been swivelled by a needle during widening.

Figure 16 is a perspective view of the right-hand feed of an embodiment adapted not only to vary the lips of the inner lifter pick presented to lift needles as shown in Fig. 8, but also to idle the pick as shown in Figs. 14 and 15.

Circular weft-knit heel and tie pockets generally consist of what may be termed a plurality of fashioned or tapered gussets. These pockets may consist of combinations of narrowed gussets and widened gussets, or either kind alone. The conventional heel or toe pocket has a narrowed gusset and a widened gusset joined together along fashioned edges by a suture. This may be termed a double-sided suture because both gusset edges or sides of the suture are fashioned. Single-sided sutures are also known, i. e., ones in which only one gusset edge or side is fashioned, the adjacent edge of the fabric being a single course or sometimes a single wale. The U. S. patent to Harry N. Sheppard No. 2,388,649, dated November 6, 1945, shows some single-sided sutures in which the gusset edge that is fashioned is a narrowed one. The machine of my present invention is useful in making either single or double-sided sutures by multi-feed reciprocatory knitting.

The invention will be shown embodied in a Scott & Williams independent needle hosiery knitting machine having the usual needle cylinder 260 which rotates and reciprocates inside a cam ring 271. The needles N move vertically in the slots in the needle cylinder, their butts projecting into cam paths in the cam cylinder, as hereinafter set forth. The cam ring and needle cylinder are supported inside the usual bedplate B and are driven from standard driving parts. As explained in the Robert W. Scott U. S. Patent No. 1,152,850, dated September 7, 1915, the machine is under the general control of a pattern chain and pattern drum (not shown). As already mentioned, the example shown in the drawings is a two-feed machine, i. e., it makes two courses of stitches for each revolution or oscillation of the needle cylinder. For this purpose there is a group of three stitch cams in the machine—a double center stitch cam 50 flanked by end stitch cams 360, 361. These end stitch cams 360 and 361 are of the usual shape for Scott & Williams single-feed hosiery machines. They are each shaped and located so as to clear needles when it is the leading cam and to knit when it is in the following or trailing position.

The double center stitch cam 50 is of novel shape and function. It is shaped to knit on both directions of movement of the needles. This cam is a double one sloping downwardly toward the center from each side. The two surfaces 51, 52 are both at about 45° from the horizontal and each surface constitutes an operating or stitch-drawing face. These two cam or stitch-drawing

surfaces 51, 52 do not meet at the bottom of the cam but terminate at separate points 53 and 54. The two points are separated from each other a distance equal approximately to say the width of seven or eight needles as they are mounted in the needle cylinder (see Fig. 13). For example, in a 400-needle, 3 $\frac{3}{4}$ " cylinder machine, these two points would be approximately $\frac{1}{4}$ " apart. In the stitch cam of the ordinary single-feed Scott & Williams model K machine, the back face of the cam, i. e., the raising side, is sloped only about 23° from the horizontal. This low angle gives time for the sinkers to be reinserted after the draw-down point to hold the stitches down by means of the nebs of the sinkers before the friction of the rising needles can force the fabric above the nebs of the sinkers. However, in the new double stitch cam both sloping surfaces must be used as stitch-drawing surfaces, so each face is of necessity 45° from the horizontal. It follows that the needles rise faster than in a single-feed machine, and "unhooking" of the stitches sometimes occurs. The separation of the two points 53, 54 relieves this by giving the sinkers S time to come in and hold the stitches down before they get above the nebs. With these separated points the first point met acts as the draw-down or stitch point and the second point met acts as the knocking-over point. It will be noted that the second point is located after the knitting has left the "robbing" area, which is normally considered as existing immediately after the draw point.

It has been found that in knitting fine-gauge fabric at high speed, any infinitesimal downward movement of the needles between the two points may cause cutting of the yarn. The bottom of the cam has therefore been shown with an upward arch or relief 58 between the two points 53, 54. In order to be sure the needles do not by any chance fail to take advantage of this relief 58, a supplemental hump 55 has been put on the usual bottom center cam 56 directly underneath the double-pointed stitch cam. In this way the needles are compelled to give relief to the yarn. It will be noted that the needles, in passing over the second point after a slight relief, bring the stitches back to the draw-point level momentarily, tending to make uniform again any irregularities which may have occurred since the first draw point was passed. The double stitch cam 50 also has shoulders 57 on each side above the stitch-drawing surfaces 51, 52 which serve as check or cover cams when the needles are rising. These cams prevent the needles from jumping over the next stitch cam.

The two feed points of the machine can be said to be located between the shoulders of the double center cam 56 and the draw-down or knitting face of each end stitch cam 360, 361.

I will first describe the embodiment of Figs. 1 to 5, 8 and 12. Formed from the lower edge of the cam path for the needle butts and between the center stitch cam 50 and the right-hand stitch cam 361 is what may be termed a central clearing cam 1 for the right-hand feed. There is a similar central clearing cam 2 between the center stitch cam 50 and the left-hand stitch cam 360 for the left-hand feed. Each central clearing cam is lower than the upper ends of the adjacent stitch-drawing surfaces of the center and end stitch cams. The low clearing cam surfaces of these cams are each characteristically located under a stitch-drawing surface which is effective on the opposite direction of movement

of the needles from the effective direction for the clearing cam. Each clearing cam is adjacent to and connects with the hump 55 on the bottom center cam 56. The upper end of each central clearing cam is set back on each side to form setbacks 3, 4, 5, 6. Each cam narrows down to a short flat 7, 8 at the top.

There is a pair of lifter picks for each feed, the usual or outer lifter pick and a novel inner lifter pick. The free or operating end of each of the so-called inner lifter picks 652, 653 is located between the center and end stitch cams. The inner and outer lifter picks 650, 651, 652, 653 are each carried on a post 9 on the bedplate B. Each lifter pick is pivotally mounted in a housing 10, 11 swivelled on one of the posts. There are springs 12 tending to hold the free ends of these lifter picks down.

The raising of the four lifter picks is effected by cams 13, 14, 15, 16 (Fig. 2). This vertical component of movement occurs when the picks are given a horizontal swivelling movement through contact with the butts of the needles N as the needle cylinder turns. The cams 13, 14 for the left and right-hand outer lifter picks 650, 651 are fixedly mounted on the posts 9. The cams 15, 16 for the inner lifter picks 652, 653 are formed on the cam ring 271. The outer end of the housing 10 of each outer lifter pick is joined to the outer end of the housing 11 of the inner lifter pick at the same feed point of the machine by a lost-motion linkage 17. The free or operating ends of the outer lifter picks 650, 651 lie in the usual notch in the upper face of the regular right and left-hand stitch cams 360, 361 when positioned to receive the needle butts. They operate on needles which are being cleared over the end stitch cam 360 or 361. The construction of all the picks is such that when a needle butt engages and causes one of the picks to swivel, it is pushed to an up position by its cam 13, 14, 15, 16. Simultaneously the linkage 17 and the spring 12 cause the companion lifter pick to be lowered to its operative position. Thus it will be noted that there are two lifter picks cooperating together at one feed so that when one raises a needle out of action, the other pick is moved down into its operative position by a movement which has both a swivelling component and a vertical or lifting component of movement. It will be noted that each pair of lifter picks, namely, one inner and one outer pick, is associated with the one feed point and that the inner pick is adapted to operate in one direction of movement of the needle cylinder and the outer pick in the opposite direction of movement of the needle cylinder. Thus each lifter pick is adapted to act on a movement opposite to that in which its companion acts. It will also be noted that while the outer pick is in only the clearing path of the needle butts, the inner pick not only lies in the clearing path of the needles in one direction of movement but actually lies underneath the knitting wave in the reverse direction. Each inner lifter pick lies in the path of, and is operative on, needles rising from the center cam. It picks leading needles out of action after they have passed under the center stitch cam and before they pass under the end stitch cam.

The stationary cam 16 for the left-hand inner lifter pick 652 and the complementary cam at the right-hand feed for the inner lifter pick 653 are sloped upwardly in a direction away from the double center cam 50 to a flat 13 slightly above the top of the adjacent end stitch cam 360 or

361. This flat 18 is also so located circumferentially with relation to the pivot points of the lifter picks that when the free end of either of the lifter picks at any feed swings up onto the flat, it has moved away pivotally out of contact with the needle butts and will remain on the flat in its upper or idle position. When one of these picks is in its lowermost position, one of the cams assists in holding the free end of the lifter pick with its lip opposite the flat 7 or 8 of the clearing cam 1 or 2. When an outer lifter pick 651, 650 is swivelled toward the center stitch cam 50, the cam 13 or 14 raises it up above the flat 18 off the lifter pick cam 15 or 16. Thus, owing to the lost-motion linkage 17, the two lifter picks at any one feed alternate in their use of the space above flat 18 as their idle position. The inner picks actually rest on the flat 18 when in this position but the outer picks clear the flat by some distance, as shown (see Fig. 4).

Because of the shoulders or set-backs 3, 4, 5, 6 in the central clearing cams, any needles descending the center cam 50 or the lower face 19 on the end stitch cam 360 or 361 take a different path from needles ascending the central clearing cam. Because of the picks 652, 653 being located in these set-backs, the descending needles pass above those picks but the ascending needles contact them. In the embodiment of Figs. 1 to 5, 8 and 12, the free end of each inner lifter pick, when in its operative position, is opposite the top of the clearing cam with its lip 20 level with the flat 7 on the right-hand clearing cam 1 or the flat 8 on the left-hand clearing cam 2. In each case the lip faces toward the preceding stitch cam. Thus the pick associated with clearing cam 1 between the center cam 50 and the right-hand end stitch cam 361 faces to the left as it appears in Fig. 1. The pick associated with clearing cam 2 located between the center cam 50 and the left-hand end stitch cam 360 faces toward the right in the same figures. Thus the lips 20 of the inner lifter picks never face the end stitch cams.

The flats 7 and 8 on the top of the central clearing cams 1, 2 are of sufficient height to clear any needles which ride over them. Thus all active needles which ride up one of these two central clearing cams will be cleared regardless of whether or not the free end of the pick is opposite the flat 7 or 8. The tops of these clearing cams are thinner than the bottoms, as can be seen in Figs. 1, 2 and 12. While the ends of the picks thus lie partly covered or overlapped by the tops of the clearing cams, the butts of the needles are all long enough to reach over the tops of the clearing cams into the path of the ends of the lifter picks. This will be seen at the left-hand inner pick 652 in Fig. 1 or in the showing in Fig. 12.

There is the usual widening pick or dropper 680 and guard cam 416 (see Fig. 15) in all the embodiments of my invention. It is located at a point circumferentially opposite the double center stitch cam 50. The dropper pick is shown with two lips 681, 682 on each side. With a double lip construction I provide controls enabling its operative end to be held either in an upper or a lower position where it will engage and pick down needles on both lips 681, 682 or only on the upper lip 681. The width of the lips may be varied as desired to take down the requisite number of needles for the particular picking sequence desired, as hereinafter set forth. In Fig. 15 the lower lip 682 is shown of a width for a single

needle, while the upper lip 681 is shown of a width for two needles.

Needles may be raised to the idle level where they will be contacted by the guard cam 416 and properly presented to the dropper pick 680 either entirely by the lifter picks or through the intermediary of stationary auxiliary cams 43, 44 (Fig. 15) located circumferentially between the lifter pick raising cams and the dropper pick. These auxiliary cams contact the needles raised by the lifter picks and raise them to a uniform level for presentation to either one or the other end of guard cam 416.

I have found it possible to vary the number of needles raised by the lifter picks. I wish to point out in general that in accordance with my invention it is not only possible to vary the total number of needles raised out of action on any given oscillation of the machine, but it is also possible to cause such raising either by both or only one of the lifter picks on each oscillation. I will describe not only the adjusting of the inner lifter picks to vary the number of needles raised out of action, but also the mechanisms by which the inner lifter picks may be thrown out of action during the making of the widened segment. I find that these methods of manipulating the picks give highly desirable sutures and a variety of suture and segment shapes not heretofore obtainable in a single-feed machine.

Referring to Figs. 5 and 8, I will describe the means by which the number of needles lifted out of action by the outer lifter picks 650, 651 can be varied. The free or operating end of the right outer lifter pick 651 has upper and lower lips 21, 22. When the position of the pick is such that the leading active needle moves into the upper lip 21, it will be obvious that the second needle butt will be raised in the lower lip 22 and two needles will be raised out of action. On the other hand, if the butt of the leading active needle engages the lower lip 22, only one needle will be raised. The left-hand outer pick 650 has similar lips. To vary the position of the right-hand pick with relation to the right-hand stitch cam 361, a swivelled cam piece 23 is provided. This cam piece is swivelly mounted on the cam ring 271 (Fig. 5). When in upright position similarly to the swivel piece 28 shown in Fig. 8, it holds the lower lip 22 in line with the approaching needle butts. When it is tilted toward the center cam 50, as shown in Fig. 5, it allows the spring 12 to hold the free end of the pick down at such a level that the butt of the leading active needle will engage in the upper lip 21. To move this cam piece 23 from one position to the other, there is a link 24 joined to a horizontal disk 25 at a point off-center. This disk is carried by a vertical pin 26 on the bedplate B of the machine (see Fig. 1). The disk in turn is operated by a wire link 27 going by means of suitable connections to the main pattern drum (not shown), and the link is moved by the cams, or absence of them, on the main pattern drum. There is a similar cam piece 28 and connecting link 29 also fastened to the disk 25 controlling the operating position of the left outer pick 650 similarly.

In Figs. 6, 7 and 13 I have shown a modification in which not only the outer lifter picks 650, 651 are adjustable, but also the inner lifter picks 654, 655. For this purpose I provide swivelled cam pieces 30, 31 fastened to the cam ring 271 underlying the lower or operative position of the free ends of the picks. When these swivelled pieces are upright, as shown for instance in Figs.

7 and 13, the picks 654, 655, in their operating positions present only the lower lip 32, while when those swivelled pieces are tipped in a manner similar to the swivelled piece for the outer pick shown in Fig. 5, the pick will be in its lowermost position and the upper lip 33 will be the first one to be contacted by a needle butt. The lips 32, 33 shown in these figures each are wide enough to take only a single needle. Therefore when the swivelled piece 30 or 31 is tipped, two needles will be raised by the corresponding inner lifter pick and when it is in the upright position of Fig. 7, only one needle will be raised at a time. Obviously, of course, the widths of the lips can be varied so as to pick a total of three or four needles, if desired. These swivelled pieces are operated by links 34, 35 connecting to a second disk 39 on the same vertical pin 26 which carries the disk 25 for the outer lifter pick adjustments. A wire 38 running to another cam path on the main pattern drum can be used to turn the disk.

In Fig. 13 is also shown the relation of the double-pointed cam to the sinkers and the usual sinker cam cap used in this and other constructions according to my invention. It will be seen that the cam path for the sinkers is such that said sinkers are withdrawn at the first or draw point 54 of the cam. After the sinkers pass the line 69 which indicates the end of the "robbing" area they are fully inserted not later than the time that the needles rise so that the stitches on them reach the sinker nebs. This action causes the knocked-over or cast-off stitch to be pushed in back of the needle and also prevents unhooking of the stitches as the needles rise on the clearing cam.

With the modification of Figs. 6, 7 and 13 it will be seen that either one, two or more needles can be lifted out of action at each course; namely, a total of either two, four or more needles for each oscillation.

I will now describe the mechanism by which the inner lifter picks can be thrown out of action as far as concerns lifting needles themselves. This involves eliminating one of the components of movement of those picks. The construction is shown in Figs. 14 and 15. In Fig. 14 I have chosen to render the inner lifter picks 652, 653 inactive during the widening of the heel. At the same time they retain their function of resetting the outer lifter picks on each oscillation of the machine. Similarly to the first embodiment, the inner picks 652, 653 and the outer picks 650, 651 are connected by adjustable lost-motion links 17a so that one inner pick 652 and its companion outer pick 650 are linked together, and the other or right inner pick 653 and its companion outer lifter pick 651 are linked together. By means of the lost-motion links 17a, the swivelling or swinging of one pick when contacted by a needle butt resets its mate for the following oscillation in the other direction.

In Fig. 14 there are cams 46, 47 for giving the inner lifter picks 652, 653 their vertical component of movement so as to raise needles to the inoperative position. These cams are pivotally mounted on the cam ring 271 and their position is controlled by means of links 48 connecting them to a disk 49 mounted on the vertical operating pin 26 on the bedplate B. The operative position of the cams is adjusted by eccentric buttons 65. The turning of the disk is caused by a wire 40 attached to any convenient control mechanism in the machine, such for example as the main pattern drum (not shown).

It will be noted that these movable cams 46, 47 when raised merely provide the lifting component of movement for the inner lifter picks. When the cams 46, 47 are lowered the picks ride on horizontal stationary cam surfaces 41, 42 formed on the cam ring.

When it is desired to make the two inner lifter picks inactive as far as concerns needles raised out of action during the making of a widened segment, the sequence of operations is as follows. During the narrowing, both the inner and outer lifter picks at each feeding point are in operation, raising one needle each. When the widening is reached, it is desired to throw two of the narrowing picks out of action and to bring into action a widening pick adapted to lower three needles at a time. In this way three needles are added at each oscillation and one needle subtracted, giving a net increase of two needles at each oscillation. To put the lifter picks in this condition the disk 49 is turned clockwise by the wire 40 acting under the influence of a cam on the main pattern drum, thereby lowering the lifter pick cams 46, 47 to their inoperative position. With these pivoted pick cams lowered out of action when the inner lifter picks 652, 653 are contacted by oncoming needles, they merely swing or swivel in a horizontal plane along the surfaces 41, 42 and do not raise any needles. This horizontal motion of the pick, although it does not raise needles, does reset its companion outer lifter pick to its operative position. With this set-up it will be seen that the desired result of one needle taken out of action at each oscillation of the machine is obtained. Assuming that the active group of needles is approaching the right-hand pair of lifter picks, as shown in Fig. 14, the first needle will be raised out of action by the right-hand outer pick 650 to join the group of inactive needles. (In Figs. 1 and 2 this is the pick at the left side of the figures.) The remainder of the group of active needles will pass under the outer pick and be led down under the shoulder 57 of the double center cam 50. There they will be pulled down to a position just above the inner lifter pick 652 and under the double center cam. It will be observed that owing to the set-backs and the shoulder 57, in spite of the placing of the inner lifter pick below the center cam, needles passing the center stitch cam from right to left take a different path from needles passing from left to right. As viewed in Fig. 1 where the pick 652 is on the left, only the needles moving from right to left will contact that inner lifter pick 652. The situation is analogous at the other side of the center cam 50 when the needles are moving in the other direction.

After passing under the double center stitch cam, the needles are raised at the left-hand clearing cam 2, when they will ride into the shoulder 6 and engage the inner lifter pick 652 (see Fig. 2). However, when the pivoted inner lifter pick cam 46 is in its lower or inoperative position, the inner lifter pick thereupon merely swivels along the horizontal surface of the stationary lifter pick cam surface 41 until in its swinging movement it clears from the needles and the needles are free to proceed on their active path.

When the inner lifter picks are in active position, as during narrowing, and the needle butts come up the left-hand clearing cam 2 and into the shoulder 6 engaging the left-hand lifter pick 652 as before, the first needle of the active group will be raised sufficiently out of action so that when released from the lifter pick it will engage

a stationary cam 43 (see Fig. 14) which may be termed an auxiliary needle clearing cam. This auxiliary cam 43 will complete the raising of this needle to the inactive level and the second course knitted on that oscillation of the machine will be knitted on the remainder of the group of active needles. There is a similar clearing cam 44 adjacent the right-hand feed.

On the last forward or run-down stroke of the widening segments of the heel or toe, the lifter pick cams 46, 47 are brought into full action by turning of the disk 49 counterclockwise. As a result the left-hand inner lifter pick 652 will be raised by the first needle of the active segment to inactive position. In this position it will be out of the path of the needles during the leg and foot. This action resets the outer pick for subsequent operations. The right-hand inner lifter pick 653 does not need to be raised out of action because the needles will be clearing over the top of the right-hand stitch cam 361 in round-and-round knitting and therefore will pass over the inner lifter pick 653 as it rests in the set-back of the right-hand clearing cam 1.

It will be seen that the above embodiment illustrates machines in which the needles, after knitting at a first feed, rise to clear under the third stitch-drawing surface before riding down the fourth surface to form a second course of knitting, and that there are means to move the leading needle to inactive position before the needles ride down at the even feed or feeds.

It is desired to point out that by having two lifter picks at each feed point and so arranging the means which control them that one of them can be prevented from lifting any needles out of action while the other of the pair continues to lift needles out of action, it is possible to get a tremendous variety of widened segments of fabric in a heel or toe. The selection of sutures and segments obtainable by this feature when the parts are so manipulated during the making of a widened or narrowed segment is much greater than the variety obtainable in single-feed reciprocatory knitting and gives improved sutures.

By means of the extra lip on the outer lifter picks—or, for that matter, on the inner lifter picks—it is possible to vary the number of needles lifted out of action. If an extra needle is added between widening and narrowing, it will determine which of the pair of courses thrown down into action by the dropper will have its beginning at the front of the returned needles. This would stagger the courses in the narrowed and widened segments. This is desirable as it affects the closeness of the gored suture.

Obviously a machine may have double-lip inner lifter picks such as shown in Figs. 6, 7 and 13, in combination with the idling of those picks as shown in Figs. 14 and 15, if desired to produce any particular picking sequence. The combined mechanism for this at the right feed is shown in Fig. 16. It consists of the parts shown in Fig. 7 plus a swivelled lifter pick cam 64 with eccentric adjusting button 65 and a link 66 to a third disk 67 on the post 26. There is a wire link 68 to the pattern drum (not shown). With such a structure the picking can be varied and the courses in the narrowed and widened segments staggered at will so as to give any desired variations in the suture or even produce a suture with a pattern. Thus one might start the suture by picking one needle up out of action with the outer picks, leaving the inner picks out of action. The next step would be to bring the inner picks into action and

5

pick one needle at each of the inner and outer picks. One might then shift the positions of the outer picks so that while the inner picks continue to lift one needle out of action the outer picks take two needles out of action and, for a final step, pick two needles up out of action at each inner and outer lifter pick.

In Figs. 9, 10 and 11 I have shown a modified form of inner lifter pick. In the other figures of the drawings the free ends of the lifter picks all terminate behind the flats 7, 8 of the central clearing cams 1, 2 and rest on the shoulder behind those flats. In Figs. 9, 10 and 11 the inner ends of the inner picks 656, 657 project completely across the upper ends of the central clearing cams and rest in notches 59, 60. As can be seen in Fig. 10, these notches are on the side of the central clearing cams away from the double center cam 50, leaving short portions 61 of the top or flat of the clearing cam unimpaired and with the lip 20 on the level with this portion 61 of the flat. Thus it will be seen that needle butts riding up the clearing cams 62, 63 from the side toward the double center stitch cam 50 will ride into the usual notch 6 or 3 onto the portion 61 of the flat and into the lip 20. The curved back of the free end of the lifter picks will help in avoiding damage to the machine if at any stage in the knitting while the lifter pick is in this lower or operative position a needle should rise up one of the center clearing cams from the outer side, come into the set-back 5 or 4 and contact the back edge of the pick.

Having set forth examples of my novel structure, I will now list some of the picking sequences obtainable by their use. By proper interrelation of the sizes of the lips on the picks, the changes in the lips presented to the needle butts being raised out of action or lowered into action and the variation in the number of lifter picks in action at various times in the knitting cycle, almost any desired interrelation of the narrowed and widened segments or any length of suture can be obtained.

First referring to typical sequences obtainable by my invention in which the net number of needles changed during the narrowing or widening is two needles, I start, of course, with the sequence in which each lifter pick lifts one needle out of action on each oscillation during narrowing. When widening is reached, the inner and outer lifter picks continue in action, lifting one needle out, and the dropper pick pulls four needles down into action on each oscillation. In this way the net change in both narrowing and widening is kept at two needles.

The above sequence can be varied as follows. During narrowing each lifter pick will lift one needle out of action, making a total of two for each oscillation. During widening the inner lifter picks will be thrown out of action as shown in Figs. 14 and 15, and the dropper pick, either by change in the size of the lips or by varying its position with relation to the approaching needle butts, will bring three needles into action on each oscillation. This will make a net change of two needles brought into action by the dropper pick for each two courses, i. e., for each oscillation.

In some cases a suture of shorter length is considered desirable. Then a net change of three needles is indicated. To achieve this, the lifter picks of Figs. 1-5, 8 and 13, instead of being elevated so that the needle butts meet only the lower lip, will be left in their lowermost position and

one needle will be raised on each lip of the outer picks. The inner pick will raise one needle, as shown in these same figures, making a total of three needles raised out of action on each oscillation during narrowing.

During widening the swivelled cam pieces will raise the outer lifter picks so that only the lower lip is engaged by the needle butts and therefore only two needles will be raised out of action on each two courses, namely, one on the outer lifter pick and one on the inner lifter pick. At the same time the dropper pick 680 will have lips on it such that it will drop five needles into action on each oscillation. This leaves a net of three needles brought into action during widening for each two courses, giving a shorter suture than in the previous examples.

A variant of the above picking sequence for the short suture but which also gives a suture of a short length, is one in which the narrowing operation is the same as in the previous sequences but the dropper pick will bring only four needles back into action. To compensate for this reduction in the number of needles brought back into action so as to leave the net number at three, the inside lifter picks will be completely thrown out of action, as shown in Figs. 14 and 15. Since the outer lifter picks lift only one needle out of action on each oscillation, the net total drawn down into action during widening is three, the same as were thrown out of action during narrowing.

Another variant of these short suture sequences is to have the outer lifter picks raise two needles out of action on each oscillation and the inner picks one during narrowing. During widening the dropper pick brings five needles down into action, the inner lifter picks will be thrown out of action entirely and the outer picks will pick up two needles. This gives the same net of three needles but in a different manner so that the interloping at the suture is different.

It will therefore be noted that while the first sequence described is exactly the same as in a single-feed gusset heel, my novel mechanism makes it possible for the first time to produce a two-feed heel almost identical in structure at the suture with a single-feed heel. It will also be noted that this has the advantage of closing up the eyelets in a two-feed heel and that if single-sided gussets are made, as in the Sheppard Patent No. 2,388,649, above mentioned, my structure has the advantages of a single-feed heel and yet it is made on a multi-feed machine.

It will further be seen that all this is obtained in a particularly advantageous way by the use of my double-pointed center stitch cam, though it should be understood that my said cam has many of its advantages if used in multi-feed machines which lack the picking sequence advantages of my structure above described. It should further be noted that the location of my inner lifter picks and the set-backs in the clearing cams, in combination with the swivelled cam pieces for eliminating the vertical component of movement of the inner lifter picks without affecting the swivelling action of the pair of picks at any feed, is a novel feature of great value which does not interfere with any of the other needle manipulations in an independent needle hosiery machine adapted to start up from the bare needles and make a complete stocking with a turned welt. One great advantage of locating clearing cams under the stitch-drawing surfaces is the reduction in length of the space occupied

by the knitting cams which is thereby obtained.

I claim:

1. A circular independent needle knitting machine having a series of feed points adapted to feed yarn to knit multi-feed in both a reciprocatory and a rotary manner, there being a stitch-drawing surface at each feed point for each direction of knitting, characterized by clearing cams under several stitch-drawing surfaces, each such surface being adapted to be effective on movement of the needles in the opposite direction from that effective for the clearing cam under it, in combination with lifter picks adapted to move to inactive position the leading needle cleared at each such clearing cam.
2. A circular independent needle knitting machine characterized in that it has a series of feed points adapted to feed yarn to knit multi-feed in both a reciprocatory and a rotary manner and a series of two oppositely sloping stitch-drawing surfaces for each feed point, in combination with needle clearing means under the second oppositely sloping stitch-drawing surface in each direction of knitting, and means to move the leading needle to inactive position between stitch-drawing points before the needles ride down to draw the stitches at even-numbered stitch-drawing points in each direction of knitting.
3. A circular independent needle knitting machine having a series consisting of at least two feed points adapted to feed yarn to knit multi-feed in both a reciprocatory manner and a rotary manner, in combination with a series consisting of two stitch-drawing surfaces for each feed point so constructed that needles, after knitting at a first feed point in either direction, rise to clearing under the third stitch-drawing surface before riding down the fourth surface to form a second course of knitting, and means to move the leading needle to inactive position between stitch-drawing points before the needles ride down at each even feed point.
4. A circular independent needle knitting machine adapted to knit multi-feed reciprocatorily according to claim 1 in which there is a single dropper pick adapted to lower a multiplicity of needles at one time on movement in each direction.
5. A circular independent needle knitting machine according to claim 1 in which there is a group of at least three stitch cams and one of the lifter picks is located in the path of ascending needle butts between each two stitch cams.
6. A circular independent needle knitting machine adapted to knit multi-feed reciprocatorily according to claim 1 in which there is a group of at least three stitch cams, and the stitch cam at each end of the group is shaped to clear needles when it is the leading cam and to knit when it is the last cam, the center stitch cam being shaped to knit in both directions of movement, there being a lifter pick in the path of needles rising from the center stitch cam or each of such cams on each direction of movement.
7. A circular independent needle knitting machine according to claim 1 in which the machine has a needle cylinder, two feeds and a group of three stitch cams, the center stitch cam being adapted to knit on movement in either direction and the two end stitch cams being adapted to knit when the movement of the needle cylinder puts them in following position but to clear needles when in the leading position, there being a lifter pick located in the path of the needle butts between the center stitch cam and each

end stitch cam, each lifter pick being operative on needles rising from the center cam, and two lifter picks each operative on needles passing above one end stitch cam when that cam is in the leading position.

8. A circular independent needle knitting machine adapted to knit multi-feed reciprocatorily characterized by the provision of at least one center stitch cam adapted to knit on each direction of movement and two end stitch cams each adapted to clear needles when in the leading position and to knit needles coming from the center cam when in the following position, in combination with two lifter picks associated with each feed point, there being on top of each end stitch cam an outer lifter pick to raise needles to idle position when the end cam is in leading position, and there being an inner lifter pick associated with each feed point adapted to pick leading needles up out of action between their passages under two stitch cams.

9. A circular independent needle knitting machine adapted to knit two feed reciprocatorily in accordance with claim 8 characterized by the provision of linkage tying together each pair of lifter picks operating between one end stitch cam and the adjacent stitch cam, whereby operation of the outer lifter pick by needle butts lowers the inner lifter pick into operative position below the said adjacent stitch cam.

10. A circular independent needle hosiery knitting machine according to claim 8 characterized in that the center stitch cam extends above the end stitch cams and in the provision of a cam surface adapted to raise each inner lifter pick above the path of needles passing under the center stitch cam when the pick is turned by contacting needle butts, whereby leading needles coming from under the center cam will be lifted above the end cam by the inner lifter pick while the following needles pass under the end cam and knit, and the outer lifter pick of the pair makes its selection from those needles coming in the other direction of movement on top of the end cam and the following needles go under the center cam and knit.

11. A circular independent needle knitting machine adapted to knit multi-feed reciprocatorily in accordance with claim 8 characterized by the provision of means whereby the inner lifter picks can be prevented from lifting any needles out of action as desired, in combination with a linkage between the picks whereby the outer lifter picks remain in action during that time.

12. A circular independent needle knitting machine adapted to knit multi-feed reciprocatorily according to claim 8 characterized by the provision of links tying together the two picks at a point whereby when one lifter pick is swivelled by contact with a needle butt the other will be swivelled to its operative position, and cams to give picks lifting components when swivelled by contact with a needle, in combination with controls for at least one of the picks of each pair adapted to move the cam for that pick so as to eliminate the lifting component.

13. A circular independent needle knitting machine adapted to knit multi-feed reciprocatorily in accordance with claim 12 in which the outer lifter picks have a plurality of lips and there are means adapted to vary the operative position of the outer lifter picks to present different lips to the needles, in combination with a single dropper pick adapted to lower a multiplicity of needles at one time, whereby the courses in the narrowed and widened segments can be staggered.

14. A circular multi-feed independent needle knitting machine according to claim 8 characterized by the provision of a central clearing cam between the center cam and each end stitch cam and lower than the upper ends of the adjacent stitch-drawing surfaces of those cams, said central cam providing clearing cam surfaces located under stitch-drawing surfaces which are so sloped as to be effective on the opposite direction of movement of the needles from the effective direction of movement of the clearing cam surface, and the inner lifter picks being located on those clearing cams.

15. A circular multi-feed independent needle knitting machine according to claim 14 characterized by the provision of space between the center cam and the inner lifter picks to permit passage between the center cam and the inner lifter picks of needles coming over the adjacent leading end cam and going under the center cam.

16. A circular multi-feed independent needle knitting machine according to claim 15 characterized in that the space for needles between the center cam and an inner lifter pick is provided by a set-back in a central clearing cam underneath the center cam, and that the inner lifter pick when in its operative position is located in that set-back.

17. A circular independent needle hosiery knitting machine according to claim 16 characterized by the provision of a lost-motion linkage between each inner lifter pick and the adjacent outer lifter pick whereby passage of the leading needles over an end cam will lower the inner lifter pick of that pair into its set-back position operative for the stroke of the machine in the opposite direction.

18. A circular independent needle knitting machine adapted to knit multi-feed reciprocatorily, having at least one center stitch cam adapted to knit on each direction of movement and two end stitch cams each adapted to clear needles when in the leading position and to cause needles coming from the center stitch cam to knit when in the following position, an outer lifted pick on top of each end stitch cam to raise needles to idle position when the end cam is in leading position, and an inner lifter pick between a center stitch cam and each end stitch cam adapted to pick leading needles up out of action between their passages under the center stitch cam and the following cam; in combination with clearing cam surfaces located under the stitch-drawing surfaces of each center stitch cam, each clearing surface being so sloped as to be effective on the opposite direction of movement of the needles from the effective direction of movement of the stitch-drawing surface above it; the clearing surfaces being set back at their upper ends whereby needles descending a center stitch cam take a different path from ascending needles and only the ascending needles contact the inner lifter picks.

19. A circular independent needle hosiery knitting machine adapted to knit multi-feed in a reciprocatorily manner in which there is a cam group containing one or more center stitch cams adapted to cause needles approaching it or them from either side to knit, in combination with an end stitch cam in the cam group at either end thereof, each such end stitch cam being adapted to cause needles approaching it from the center cam side to knit and to clear needles approaching it from the other side, and a lifter pick between

each two cams adapted to lift out of action a needle or needles approaching from a center cam.

20. A circular independent needle hosiery knitting machine according to claim 19 in which there is present a central clearing cam between each two adjacent stitch cams, in combination with a lifter pick with each such central clearing cam adapted to lift out of action a needle or needles rising up said clearing cam from a center cam.

21. A circular independent needle knitting machine adapted to knit two feed reciprocatorily characterized by the provision of a center stitch cam adapted to knit on both directions of movement and an end stitch cam on either side of the center stitch cam, in combination with two pairs of lifter picks, one pair operating between each end stitch cam and the center stitch cam, one pick of each pair being adapted to operate on one direction of movement and the other on the opposite direction of movement.

22. A circular independent needle knitting machine adapted to knit two feed reciprocatorily in accordance with claim 21 characterized in that in each pair of lifter picks the one lifting needles coming toward the center stitch cam has a plurality of lips, in combination with means adapted to vary the operative position of that lifter pick to present different lips to the needles whereby the number of needles lifted at one feed can be changed without changing the number lifted at the other feed.

23. A circular independent needle knitting machine adapted to knit multi-feed reciprocatorily having a group of at least three stitch cams and two lifter picks associated with each yarn feed point, one of the lifter picks being located in the path of ascending needle butts between each two stitch cams, the machine being characterized by the fact that the group of stitch cams includes at least one center stitch cam having two oppositely sloped stitch-drawing faces, said two faces terminating at the bottom at two points separated a short horizontal distance from each other but at the same level, the bottom of the center stitch cam or cams being relieved upwardly between the two points at the bottom of the stitch-drawing faces; whereby on each direction of movement the first point met draws the stitch and the second point met acts as a knocking-over point.

24. A circular independent needle knitting machine adapted to knit multi-feed reciprocatorily according to claim 23 characterized by the fact that the distance between the two points at the bottoms of the stitch-drawing faces is approximately equal to the space of six to ten needles as they lie in the machine, whereby stitches drawn at the first point have left the robbing area before they reach the second point.

25. A circular independent needle knitting machine adapted to knit multi-feed reciprocatorily according to claim 23, characterized by the fact that the distance between the two points at the bottoms of the stitch-drawing faces of the center stitch cam or cams is approximately equal to the space of six to ten needles as they lie in the machine, the bottom of such center stitch cam or cams being relieved upwardly between the two points at the bottom of the stitch-drawing faces, whereby stitches drawn at the first point have left the robbing area before they reach the second point.

26. A circular independent needle knitting machine adapted to knit multi-feed reciprocatorily according to claim 23 in which there are clearing cams to raise the needles immediately after passing under the center stitch cam or

5 cams, the clearing cam surfaces being located under the stitch-drawing surfaces of the center cam, in combination with web-holding sinkers cooperating with the needles and cam means adapted to retract the sinkers at the draw point of the cam, said cam means and the distance between the two points of the double stitch cam being such that the sinkers are inserted before they reach the knocking-over point of the cam, whereby unhooking of the stitches is avoided as the needles rise on a clearing cam.

10 27. A circular independent needle knitting machine adapted to knit multi-feed reciprocatorily, having a group of at least three stitch cams and two lifter picks associated with each yarn feed, there being clearing cam surfaces under several stitch-drawing surfaces of the stitch cams, one of the lifter picks being located in the path of ascending needle butts between each two stitch cams at the upper end of one of the stitch-drawing surfaces, there being in the stitch cam group at least one center stitch cam having two oppositely sloped stitch-drawing faces, said faces terminating at the bottom at two points separated a short horizontal distance from each other but at the same level, the bottom of the center stitch cam or cams being relieved upwardly between the two points at the bottom of the stitch-drawing faces; whereby on each direction of movement the first point met draws the stitch and the second point met acts as a knocking-over point.

15 28. A circular independent needle knitting machine adapted to knit multi-feed reciprocatorily in which there are a group of at least three stitch cams, there being two end stitch cams and at least one center stitch cam in the group, each center stitch cam having two oppositely-sloped stitch-drawing faces, said two faces terminating at the bottom at two points separated a short horizontal distance from each other but at the same level, there being a relieved portion between the points, whereby on each direction of movement the first point met by the needles draws the stitch and the second point met acts as a knocking-over point.

20 29. A circular independent needle knitting machine adapted to knit multi-feed reciprocatorily according to claim 28 characterized by the fact that the bottom of each center stitch cam is relieved upwardly between the two points at the bottoms of the stitch-drawing faces.

25 30. A circular independent needle knitting machine adapted to knit multi-feed reciprocatorily according to claim 28 characterized by the fact that the distance between the two points at the bottoms of the stitch-drawing faces is approximately equal to the space of six to ten needles as they lie in the machine, whereby stitches drawn at the first point have left the robbing area before they reach the second point.

30 31. A circular independent needle knitting machine adapted to knit multi-feed reciprocatorily according to claim 28 in which there are clearing cams to raise the needles immediately after passing under the center stitch cam or cams, in combination with web-holding sinkers cooperating with the needles and cam means adapted to retract the sinkers in advance of their reaching the draw or first point of the cam encountered and to insert the sinkers later, said cam means and the distance between the two points of the double stitch cam being such that the sinkers are inserted immediately after they reach the knocking-over or second point of the

cam, whereby unhooking of the stitches is avoided as the needles rise on a clearing cam.

32. A circular independent needle knitting machine adapted to knit multi-feed reciprocatorily according to claim 28 characterized by the facts that the bottom of each center stitch cam is relieved upwardly between the two points at the bottoms of the stitch-drawing faces and that the distance between the two points is sufficiently great so that stitches drawn at the first point have left the robbing area before they reach the second point.

33. A circular independent needle knitting machine adapted to knit multi-feed reciprocatorily according to claim 28 characterized by the facts that the bottom of each center stitch cam is relieved upwardly between the two points at the bottoms of the stitch-drawing faces and that the distance between the two points is approximately equal to the space of six to ten needles as they lie in the machine, whereby stitches drawn at the first point have left the robbing area before they reach the second point.

34. In a method of producing a narrowed and widened pocket on a circular independent needle multi-feed knitting machine, the steps of knitting a plurality of courses in immediate succession on a single oscillation in one direction, during which oscillation needles are raised to clear level under the stitch-drawing surfaces at at least certain of the feeds, and simultaneously moving selected needles out of action before each knitting wave, whereby a multiplicity of courses of fabric narrowed at each course are produced in a single oscillation of the machine.

35. In a method of producing a narrowed and widened pocket on a circular independent needle multi-feed knitting machine, the steps of knitting a plurality of courses in immediate succession on a single oscillation in one direction, during which oscillation needles are raised to clear level under and between the stitch-drawing surfaces at at least certain of the feeds, and causing a leading needle or needles before each knitting wave to take yarn and then be put out of action without knitting said yarn, whereby a multiplicity of courses of fabric narrowed at each course are produced in a single oscillation of the machine.

36. In a method of producing tapered fabric on a circular independent needle multi-feed knitting machine having stitch-drawing surfaces effective in both directions for reciprocatorily knitting, the steps of knitting a plurality of courses in immediate succession on a single oscillation while clearing the needles under stitch-drawing surfaces after the first course knit in one direction and simultaneously picking needles up out of action before each knitting wave, whereby a multiplicity of courses of fabric narrowed at each course are produced in a single oscillation of the machine.

37. In a method of producing tapered fabric on a circular independent needle multi-feed knitting machine, the steps of knitting a plurality of courses in immediate succession on a single oscillation in one direction and simultaneously picking needles up out of action before each knitting wave, repeating these steps a plurality of times, thus producing a fabric segment narrowed at each course, and thereafter knitting off in one course all the needles picked out of action during narrowing, whereby a single-sided suture without eyelets is produced in multi-feed fabric.

38. In a method of producing a narrowed and

widened pocket on a circular independent needle knitting machine having stitch-drawing surfaces effective in both directions for reciprocatorily knitting adapted to knit multi-feed in a reciprocatorily manner in which there are a group of at least three stitch cams and two lifter picks associated with each feed and each pick being adapted to act on a movement opposite to that of its companion, one of each pair of picks being located in the path of ascending needle butts between each two stitch cams, the steps of making a narrowed segment by oscillatory knitting of two courses on each movement in each direction while picking one needle out of action before each course, then making a widened segment by continued oscillation and continuing to pick one needle out of action before each course and picking four needles down into action at one point only during each movement in either direction, whereby the net change at each end of each oscillation is two needles both in the narrowed and the widened segments of the pocket.

39. In a method of producing a narrowed and widened pocket on a circular knitting machine adapted to knit multi-feed in a reciprocatorily manner in which there are a group of at least three stitch cams and two lifter picks associated with each feed and each pick being adapted to act on a movement opposite to that of its companion, one of each pair of picks being located in the path of ascending needle butts between each two stitch cams, the steps of making a narrowed segment by oscillatory knitting of two courses on each movement in each direction while picking two needles out of action at one course and one needle out of action at the other course, and then making a widened segment by picking a multiplicity of needles into action as a group at one point only during each oscillation and picking out of action on each such oscillation a number of needles less than the number thrown into action by the number put out of action during an oscillation while narrowing.

40. In a method of producing a narrowed and widened pocket on a circular knitting machine adapted to knit multi-feed in a reciprocatorily manner in which there are a group of at least three stitch cams and two lifter picks associated with each feed and each pick being adapted to act on a movement opposite to that of its companion, one of each pair of picks being located in the path of ascending needle butts between each two stitch cams, the steps of making a narrowed segment by oscillatory knitting of a plurality of courses on each oscillation in each direction while picking one or more needles out of action at each course, and then making a widened segment by continued oscillation and drawing a multiplicity of needles down into action at one point only during each oscillation and simultaneously picking needles up out of action, the net number of needles picked into action on each oscillation during widening being equal to the number picked out of action on each oscillation during narrowing.

41. In a method of producing a narrowed and widened pocket on a circular knitting machine adapted to knit multi-feed in a reciprocatorily manner in which there are a group of at least three stitch cams and two lifter picks associated with each feed and each pick being adapted to act on a movement opposite to that of its companion, one of each pair of picks being located in the path of ascending needle butts between each two stitch cams, the steps of making a nar-

rowed segment by oscillatory knitting of two courses on each movement in each direction while picking one or more needles out of action before each course, and then making a widened segment by picking one or more needles out of action before every other course and picking a group of needles into action at one point only during each movement in each direction, whereby the net change at each end of each oscillation is the same number of needles in both the narrowed and the widened segments of the pocket.

42. In a method of producing a narrowed and widened pocket on a circular knitting machine adapted to knit multi-feed in a reciprocatory manner in which there are a group of at least three stitch cams and two lifter picks associated with each feed and each pick being adapted to act on a movement opposite to that of its companion, one of each pair of picks being located in the path of ascending needle butts between each two stitch cams, the steps of making a narrowed segment by oscillatory knitting of two courses on each movement in each direction while picking one needle out of action before each course, and then making a widened segment by picking one needle out of action before every other course and picking three needles into action as a group at one point only during each movement in each direction, whereby the net change at each end of each oscillation is two needles in both the narrowed and the widened segments of the pocket.

43. In a method of producing a narrowed and widened pocket on a circular knitting machine adapted to knit multi-feed in a reciprocatory

manner in which there are a group of at least three stitch cams and two lifter picks associated with each feed and each pick being adapted to act on a movement opposite to that of its companion, one of each pair of picks being located in the path of ascending needle butts between each two stitch cams, the steps of making a narrowed segment by oscillatory knitting of two courses on each movement in each direction while picking two needles out of action at one course and one needle out of action on the other course, and then making a widened segment by picking one needle out of action before every course and picking five needles into action as a group at one point only during each movement in each direction, whereby a suture is produced which has a net change of three needles at each end of each oscillation in both the narrowed and the widened segments of the pocket.

ROBERT H. LAWSON.
